(57) **CLAIM**

The ornamental design for a cleaning system trolley, as shown and described.

DESCRIPTION

FIG. 1 is a perspective view of a cleaning system trolley constructed in accordance with an embodiment of the present invention;

FIG. 2 is a top view of the cleaning system trolley shown in FIG. 1;

FIG. 3 is a left side view of the cleaning system trolley shown in FIGS. 1 and 2; and,

FIG. 4 is a front view of the cleaning system trolley shown in FIGS. 1-3.

The elements shown in broken lines are included for the purpose of illustrating environment and form no part of the claimed design. The boundary lines represented by alternating dashes and dots and showing the boundary between the claimed design and the unclaimed portions of the design are for illustrative purposes only and form no part of the claimed design.

1 Claim, 4 Drawing Sheets
